UNITED STATES PATENT OFFICE

103,043

DESIGN FOR A REAR DOOR HINGE AND PULL ASSEMBLY FOR AUTOMOBILES

Alexander Carlson, Lima, Ohio, assignor to
Superior Body Company, Lima, Ohio, a cor-
poration of Ohio

Application November 19, 1936, Serial No. 66,016

Term of patent 14 years

To all whom it may concern:

Be it known that I, Alexander Carlson, a citizen of the United States and resident of Lima, in the county of Allen and State of Ohio, have invented a new, original, and ornamental Design for a Rear Door Hinge and Pull Assembly for Automobiles, of which the following is a specification, reference being had to the accompanying drawing, forming a part thereof.

In the drawing, Figs. 1 and 2 are different side elevations of a rear door hinge and pull assembly for automobiles showing my new design.

This hinge and pull assembly is particularly in-

tended for use in connection with the rear doors of funeral and ambulance automobiles, the bar member designated 1 extending across the door from its hinge edge to near its opposite edge and serving as a pull member, and the members designated 2 and 3 being secured to the automobile body at the respective sides of the door opening.

I claim:

The ornamental design for a rear door hinge and pull assembly for automobiles, substantially as shown and described.

ALEXANDER CARLSON.
